UNITED STATES PATENT OFFICE

112,181

DESIGN FOR A SIPHON HEAD OR SIMILAR ARTICLE

Hugh J. Ross, Brooklyn, N. Y.

Application March 17, 1938, Serial No. 75,902

Term of patent 7 years

To all whom it may concern:

Be it known that I, Hugh J. Ross, a citizen of the United States of America, residing in the Borough of Brooklyn, in the city of New York, county of Kings, and State of New York, have invented a new, original, and ornamental Design for a Siphon Head or Similar Article, of which the following is a specification, reference being had to the accompanying drawing, constituting a part thereof.

I claim:

The ornamental design for a siphon head or similar article, as shown and described.

HUGH J. ROSS.
